MANUFACTURE OF LIGHT HYDROCARBONS AND THE LIKE.

1,419,121.

Specification of Letters Patent. Patented June 6, 1922.

Application filed May 18, 1915. Serial No. 29,020.

To all whom it may concern:

Be it known that I, WALTER F. RITTMAN, residing at New York, in the county of New York and the State of New York, have invented or discovered certain new and useful Improvements in the Manufacture of Light Hydrocarbons and the like, of which the following is a specification.

The invention described herein relates to a process for the manufacture of light hydrocarbons and the like and has for its object the manufacture or conversion of such products, either from crude mineral oils, or from the products thereof. The invention is not limited to the treatment of the mineral oils or their products but is adapted for the treatment of the liquid hydrocarbons or liquid hydrocarbon products obtained from bitumen, shale, coal, lignite, peat, or other substances capable of yielding liquid hydrocarbon products.

Many processes have been employed or suggested for the transformation or conversion of the above materials into the desired hydrocarbon products, but all of them involved the distillation of the material being treated.

In order to transform or convert the material having a high boiling point, i. e., above 150 degrees C., to a product or products having a relatively lower boiling point, the heavy materials must be cracked, which requires a temperature considerably above the normal boiling point of the material being treated. The higher the temperature to which the material is subjected, the larger the percentage of the low boiling point products produced.

As in distilling operations any increase of temperature above the normal boiling point of the liquid cannot be obtained unless the pressure on the liquids is also increased, a point is soon reached beyond which the temperature cannot be safely increased. Practice has shown that it is difficult and dangerous to continuously employ a temperature exceeding 400 degrees C. and the necessary accompanying pressure of above 100 pounds per square inch.

In order to reduce the danger incident to heating large quantities of the heavy materials approximately to 400 degrees C., it has been suggested to atomize the heavy materials prior to subjecting them to such

temperature in a still. The injection of small quantities of the heavy materials in a finely divided condition into a heated chamber is but a modification of the distilling operation. The material entering the heating chamber is a liquid in finely divided condition, and this method has the advantage of greatly increasing the surface of evaporation. In the usual distilling method and in the modification referred to, cracking is effected while the material is in a liquid state, and the residue of unconverted heavy material is large.

It is characteristic of my improved method that cracking is effected after the material has been gasified. The material is transformed from a liquid to a gaseous form and then subjected to temperatures at which the gaseous material will be cracked, permitting of the formation of new combinations, the formation of such new combinations being promoted by maintaining the gases under a suitable pressure.

In the practice of my invention the heavy material is continuously fed into a highly heated zone formed by a suitable receptacle in which suitable provision is made whereby the material is flashed or instantaneously transformed into a gaseous condition. The gases are passed immediately into a zone in which it is preferred to maintain a temperature higher than that in the gasifying zone. While practice has shown that a temperature not less than 400 degrees C. should be maintained in the gasifying zone and an equal, but preferably a much higher, temperature should be maintained in the second or cracking zone; it will be understood that the temperature in the gasifying and cracking zone will vary with the character of the hydrocarbon materials to be treated, i. e., the higher the boiling points of the material treated, the higher the temperatures in such zones should be to attain the best results. As, for example, it is believed that when treating materials having boiling points above 250 degrees C., the best results will be attained by maintaining temperatures of about 550 degrees C. more or less, in the respective zones.

In the cracking operation, a large number of different gases are formed, ranging from hydrogen to hydrocarbons having boiling points the same as or even higher than those

in the materials treated. The cracking permits of the formation of new and more volatile combinations, the majority of which will be condensable at temperatures of 30 degrees C. and upwards. The maintenance of gases resulting from the cracking, such as hydrogen, methane, ethylene, ethane, etc., having boiling points below 30 degrees C., and which will, for the purposes of this 10 case, be hereinafter termed permanent gases, in the cracking zone, is an important feature of my improved process as will be herein-after stated.

In order to promote the formation of the 15 new combination of hydrocarbons more volatile than the materials treated, pressure above atmospheric pressure should be maintained in the second zone.

It is well known that in chemical reactions 20 there is a tendency to establish and maintain a state of equilibrium. As for example, in the cracking of the gaseous hydrocarbons as above described, two classes 25 of gases are formed, i. e., those condensable at temperatures above 30 degrees C., and those which remain uncondensed at temperatures of 30 degrees C., and above, such as the permanent gases referred to. If the condensable gases be withdrawn or removed, 30 the cracking being continued, the other, or permanent gases, or a very considerable proportion thereof, being in the sphere of reaction, there will be a tendency to restore the equilibrium and form the condensable hydrocarbons rather than those 35 not condensable at temperatures above 30 degrees C. This tendency to form the condensable hydrocarbons will be promoted by high concentration or increase of the 40 density of the permanent gases in the sphere

of reaction. To this end, a pressure substantially above atmospheric pressure is maintained in the reaction zone.

While the desired pressure can be produced in any suitable manner or by any 45 suitable means, it is preferred to obtain such pressure by controlling the discharge of the gases from the reaction zone. It will be understood that although the best results can be attained by employing for a given 50 material, a certain temperature and a certain pressure, these two are in no way inter-dependent. It is generally preferred to use high pressures with high temperatures, and these pressures and temperatures are generally 55 those which cannot be obtained in a two phase system.

While the pressures employed will vary with the character of the material treated, and the character of the products desired, 60 the best results will be obtained by maintaining a pressure of about 100 pounds and higher in the generating zone, the efficiency of the process increasing as the pressure employed is increased.

It is only necessary to experimentally determine the combination of pressure and temperature which yields maximum results when applied to the vapors of any particular oil and then apply such combination.

While a pressure of about 100-lbs. has been indicated, it will be understood that this is not to be considered as a critical or limiting pressure. This will be apparent (as pointed out in my application Ser. No. 75 11,398 filed Mar. 15, 1915 of which this application is a continuation) from consideration of the equation representing the type reaction.

$$xA \rightleftharpoons yB + zC$$

$$\text{Constant} = \frac{(\text{Concentration B})y + (\text{Concentration C})z}{(\text{Concentration A})x}$$

80 where xA represents the high boiling point hydrocarbons to be converted into lower boiling point hydrocarbons; where yB represents the lower boiling gasoline hydrocarbons; and zC represents hydrogen and 85 non-condensable hydrocarbons (CH_4 , C_2H_6 , C_2H_4 , etc.). Physical chemistry recognizes that any such system tends to reach an equilibrium between its various constituents. It is evident that when the end products 90 represented by zC are kept in the sphere of reaction, the tendency is for xA hydrocarbons to form yB hydrocarbons, in order to satisfy what the chemist terms "equilibrium conditions." It is further evident 95 that the greater the concentration of zC the more pronounced is the tendency of xA to form yB and not form zC . In the conventional type of still these constituents

termed zC , being lighter in weight than the liquids, constantly pass up and out of the 100 sphere of reaction; whereas an important feature of this process involves their retention in the sphere of reaction.

It is evident, therefore, that any substantial increase in pressure sufficient to 105 produce a high concentration or increase of density of the permanent gases in the sphere of reaction will tend to increase the formation of low-boiling hydrocarbons.

While not necessary it is preferred that 110 gasification should be effected above the reaction or cracking zone, and that the condensable gases be removed at a point below the cracking zone, so that advantage may be taken of the difference in the character 115 or nature of the permanent and condensable gases, the former being the lighter and

therefore having a tendency to remain in or to return to the reaction zone, as is desired in the practice of this process.

The shape and dimensions of the portion 5 of the apparatus forming the reaction or cracking zone can be varied within wide limits, but the portion of the chamber forming this zone should be made of a size or dimension suitable for such relative movements of the gases as will promote the separation above referred to, or movements or subsidence of the condensable gases from the cracking zone, and a relatively slower subsidence of such permanent gases as may be 10 carried along by the condensable gases as they move away from the cracking zone.

The temperature employed in the practice 15 of my invention depends upon the character of the hydrocarbon material to be treated, and the character of the products desired. But as it is generally desired to convert as much as possible of the material treated into products having a relatively lower boiling point the temperature employed 20 for gasifying should be sufficiently high to insure the substantially instantaneous gasification of so much of the material as is capable of gasification under practical conditions, and the temperature in the cracking zone should be higher than that in the 25 gasifying zone, and the conditions above stated will depend in commercial operations largely upon the character of the material treated and the product desired.

30 By expanding the heavy hydrocarbons in small quantities into gases and then subjecting these gases to high temperatures and high pressures, the speed or velocity of reaction incident to high temperatures is attained 35 without incurring any great liability to blowouts.

It will be understood that in the practice 40 of my invention, the conditions of operation, i. e., temperature, pressure and time, can be 45 changed and adapted to produce a desired product in greater quantity or a different character of product, or either or all of them at will. By reason of having the reaction occur 50 substantially in the gaseous state, a flexibility in the application of the above conditions is permitted which is impossible in any distillation process, or in any other process involving the retention of liquids in the sphere of reaction. It is well known that 55 in a two-phase system, such as occurs when both liquid and gas are present in the reacting zone, temperature and pressure are interdependent—one being fixed by the condition chosen for the other; whereas, in a 60 single phase system, such as occurs when the product to be treated is in the reacting zone in a gaseous condition, apart from the liquid, it is possible to exercise control over each one of the above stated conditions or 65 variables, selecting any temperature and

any pressure below the condensation pressure for that temperature and retaining the gases for any required time under the chosen conditions of operation. It is characteristic of my improved process, that by controlling the 70 feed of the material to be generated into gases, or by regulating the flow of the converted gases into or from the zone of reaction, or by varying the length of the reaction zone, it is possible to regulate over wide 75 limits, the time or duration of the reactions effected, and regulate at the same time, the pressure and temperature at will, each independent of the other. It is impossible to do this in any two phase system. 80

My process is well adapted for the conversion of crude mineral oils or the products thereof, or of liquid hydrocarbons, or liquid hydrocarbon products obtained from bitumen, shale, or other substances capable 85 of yielding liquid hydrocarbon products into gasoline hydrocarbons having boiling points below 150 degrees C. The process not only recovers the gasoline hydrocarbons from crude mineral oils originally containing the 90 same, but also materially increases the yield thereof, as a very large percentage of the heavy hydrocarbons remaining after the removal of the originally contained light hydrocarbons can be converted into gasoline 95 hydrocarbons having boiling points below 150 degrees C.

The best conditions for the manufacture 100 of gasoline hydrocarbons having boiling points below 150 degrees C. from the above material will be a temperature in the cracking zone ranging approximately between 500 and 700 degrees C, and a pressure of about 300 pounds per square inch and above.

For the purpose of illustration, I have 105 shown in the accompanying drawing an exemplification of a simple form of apparatus adapted to the practice of this invention, although it will be understood that the particular apparatus shown is but typical of 110 many others having the same capabilities. It is also contemplated that any convenient and efficient source of heat may be substituted for the electricity which I have used in the experimental apparatus. 115

Figure I is a side view of the apparatus, partly in sections. Figure II illustrates a type of fractional condenser that may be used with this or any similar apparatus.

Referring to the drawing, A indicates a 120 chamber or receptacle capable of withstanding the pressure of the gases within the same and the upper portion of this chamber constitutes the vaporizing section or zone, and the remaining portion constitutes the hydrocarbon cracking zone. a is a resistance wire, properly insulated, in contact with A which is incased in a protective coating of asbestos or other material adapted to prevent excessive radiation of heat. b and d are binding 125 130

posts from which conductors lead to a proper source of electrical energy. *c* is a conducting rod through which one end of the resistance coil is connected to bind post *d*. *B* is a rheostat used for controlling and regulating the current supplied. *e* is a branch tube opening into *A* through which the pyrometer couple is introduced whereby the temperature prevailing may be read from an appropriate instrument. *f* is a rod to support a perforated disc *m* which supports a quantity of filling material *g* introduced into the upper portion of *A*. This filling material may be metal balls or any other material which will serve as an efficient spreading surface for vaporizing the oil used, as well as a heat conductor and heat disseminator. It will be understood that the use of this filling material is not indispensable to the operation of my invention as the gasification of the material being treated may be facilitated or accomplished by any other suitable means. *C* is a feed cup or receptacle for supplying oil to *A* above *g*. The pressure in the upper part of *C* is equalized with that in tube *A* through an equalizing connection 2. *A* may also be connected with a suitable gauge for reading the pressure therein. *D* is a condenser which leads condensable gases through a pipe *H* to a receptacle *E* for the collection of liquid distillates. *F* is a pipe and *G* a release valve through which the gaseous products evolved during the process may be permitted to escape into a gas holder not shown and by shifting this valve the desired pressures may be maintained in the chamber *A*. In the form of apparatus shown in Fig. 1 a condenser *D* is cooled to a sufficient degree to condense all vapors. Condensate passes through *H* to a collecting vessel *E* from which said condensate may be withdrawn and fractionally distilled. In case a fractional condenser is desired the equipment shown in Fig. 2 would be put in place of *E* in Fig. 1 and the temperature of condenser *D* maintained so as to condense only the heavy hydrocarbons and permit the more volatile vapors to pass to a secondary condenser *M* to be collected in receptacle *N*.

In the manufacture of gasoline with the type of apparatus above described and shown in the accompanying drawing, I proceed substantially as follows: The cracking or reacting chamber heated to the desired cracking temperature of the material by passing an electric current of appropriate wattage through the heating element *a*. When the tube *A* and the filling material *g* contained therein have attained the appropriate temperature, the feed is opened and the material is permitted to enter the upper part of the tube *A* where it spreads over the filling material and is flashed or substantially instantaneously transformed into gas.

In the meantime the valve *G* has been closed in order to bring the concentration of permanent gases to the desired point. After the desired pressure has been attained, valve *G* can be opened from time to time to release excess pressure created in *A*. The hydrocarbon gases pass into the cracking zone, of the tube *A*. After passing through the cracking zone, the hydrocarbon gases are condensed and collected in receptacle *E*, thereby being removed from the sphere of reaction.

It is characteristic of my improved process that the material treated is gasified, and that cracking is effected in the gaseous phase. And further it is characteristic of the invention that the three conditions which are involved in converting hydrocarbons, i. e., temperature, pressure and time, are in no way interdependent. That is to say the temperature can be varied without changing the pressure, and vice versa, and the rate of movement of the gases through cracking or reaction zone can be regulated. In other words, the conditions above stated can be changed simultaneously or independently or in any desired order, or to any desired extent, at will, or as required to produce the desired result.

By the term "substantially uniform mixture" as herein employed, is meant a mixture containing substantially the entire range of hydrocarbons found in the original liquid material which it is proposed to treat. In other words, all the hydrocarbons from the lightest to the heaviest, regardless of respective boiling points, which are found in the original material, are converted into gases at substantially the same time so that there is a constant uniformity in the mixture of gaseous hydrocarbons which are to be cracked in the apparatus.

I claim:

1. In the conversion of high boiling carbon oils into lower boiling hydrocarbon oils, the process which comprises passing the same downwardly through a vertical, externally heated, unobstructed chamber under a pressure higher than atmospheric and maintained at a cracking temperature, the conditions within such retort being such as to permit free fall of the introduced material therethrough.

2. In the manufacture of gasoline from heavy petroleum oils, the process which comprises passing the same into an upper portion of a vertical, externally heated, unobstructed reaction chamber maintained at a cracking temperature and withdrawing produced vapors and gases from the bottom of such chamber.

3. In the manufacture of gasoline from heavy petroleum oils, the process which comprises injecting the same into the top of an externally heated, substantially unobstruct-

- ed, vertical chamber maintained under heavy pressure and at a cracking temperature and withdrawing produced vapor and gases from the bottom of such chamber.
- 5 4. The process herein described which consists in subjecting hydrocarbons in a gaseous condition to a temperature of not less than 400 degrees C. and to a pressure of not less than 100 pounds per square inch and
- 10 10 effecting a gravity separation of the mixture and condensing the hydrocarbons having boiling points not lower than 30 degrees C.
- 15 5. The process herein described which consists in continually passing a substantially uniform mixture of hydrocarbon gases through a heated chamber maintained at a temperature of not less than 400 degrees C. and of such size as to permit of a rapid subsidence of the heavier gaseous hydrocarbons
- 20 20 and a relatively slower subsidence of the lighter hydrocarbon gases and in which chamber the gaseous hydrocarbons are subjected to a pressure of not less than 100 pounds per square inch.
- 25 6. The process herein described which consists in continually subjecting a substantially uniform mixture of hydrocarbon gases to a temperature ranging between 500 and 700 degrees C. and to a pressure of about 300
- 30 30 pounds per square inch and upwards and condensing the gasoline hydrocarbons having boiling points below 150 degrees C.
7. The process herein described which consists in subjecting a substantially uniform mixture of hydrocarbon gases to a temperature ranging between 500 and 700 degrees C. and to a pressure of about 300 pounds per square inch and upwards and condensing the gasoline hydrocarbons having boiling points below 150 degrees C. 35
8. The process of treating oils containing liquid hydrocarbons having boiling points above 150° C. at atmospheric pressure, to obtain therefrom low-boiling gasoline hydrocarbons, which comprises vaporizing the oil, 40 45 passing the substantially uniform mixture of hydrocarbon vapors through an externally heated substantially unobstructed vertical chamber, maintaining such vapors at a temperature of not less than 400° C. and at superatmospheric pressure, withdrawing and condensing the hydrocarbons having boiling points not lower than 30° C., the conditions of pressure and temperature in, and rate of flow through said chamber being 50 55 so adjusted as to promote the formation of gasoline hydrocarbons.

In testimony whereof, I have hereunto set my hand.

WALTER F. RITTMAN.
